Primary Examiner — Dana Meyrow(74) *Attorney, Agent, or Firm* — Kanika Radhakrishnan; Evergreen Valley Law Group(57) **CLAIM**

The ornamental design for an opaque sealed container, as shown and described.

DESCRIPTION

FIG. 1 illustrates a top, front, left side perspective view of an opaque sealed container according to the present invention;

FIG. 2 illustrates a top plan view thereof, shown at a reduced scale;

FIG. 3 illustrates a rear elevation view thereof, the front elevation view excluding the top surface of the opaque sealed container being identical, shown at an enlarged scale; FIG. 4 illustrates an exploded top, front, left side perspective view thereof shown at a reduced scale, showing the interior lid; and,

FIG. 5 illustrates an exploded top, front, left side perspective view thereof, with the interior lid removed.

The broken lines in the drawings, including the unshaded inside bottom surface of the container shown in FIG. 5, illustrate the portions of the opaque sealed container that form no part of the claimed design.
